UNITED STATES PATENT OFFICE.

HENRY LEWIS DAVIS, OF LONDON, ENGLAND.

METAL-SHANK BUTTON.

1,072,921.

Specification of Letters Patent.

Patented Sept. 9, 1913.

Application filed September 17, 1908. Serial No. 453,546.

To all whom it may concern:

Be it known that I, HENRY LEWIS DAVIS, a subject of the King of England, residing at London, England, have invented certain new and useful Improvements in Metal-Shank Buttons, of which the following is a specification.

This invention relates to metal shank buttons and has for its object improvements in the construction of the shank thereof whereby any possibility of the attaching thread being cut by contact with sharp edges is obviated; a substantially flat surface makes contact with the material of the garment or other article to which the button is applied—resulting in the button remaining parallel with the said material instead of drooping; a maximum distance between the shank and edge of the button is obtained; a good clearance between the material and the back of the button is provided, and a guide formed to direct the needle through the thread holes or openings in the shank while the button is being attached to the article to which it is to be applied.

For attaining the objects above set forth, the present invention consists essentially in providing the back disk or shell with an improved form of shank, as hereinafter described, which may either be integral with said back or shell, or connected therewith in such a manner as to permit the button to revolve around the shank.

In order that the invention may be clearly understood I will now proceed to more particularly describe it with reference to the accompanying drawings, whereof:

Figures 1, 2 and 3 are respectively a front and back view and a sectional elevation of one form of button to which a metal shank, made in accordance with this invention, has been applied. Fig. 4 is an inside view of the back disk or shell with its integral metal shank; Fig. 5 is a side elevation of Fig. 4; Fig. 6 is a sectional view of a modified form of button adapted to turn about a shank made in accordance with this invention, while Figs. 7, 8 and 9 are examples of fancy buttons which may be provided with my improved shank in the same manner as the plain type of button shown in Figs. 1 to 3.

In carrying out this invention in accordance with the construction shown in Figs. 1 to 3, I press or otherwise form out of a sheet of metal or other suitable material, two disks or shells, from which the button-front *a* and

the button back *b* are respectively formed. As is usual and well-known in button making, the front shell *a* is made slightly larger than the back shell *b* so that a rim *c* on the latter can fit within a rim *d* on the former, and permit the two shells to be connected by swaging or pressing the outer rim *d* of the front part (which may or may not be provided with a cloth or other covering *e*) over the inner rim *c* (Fig. 3), in manner well-known in button making.

The shank of the button, the improved construction of which (shank) is the subject of the present invention, is, in the example of button now being described, conveniently formed at the same time as the back shell is stamped out, the stamping tool being adapted to press up the central part of the back shell *b* to form a projecting part *f* having a substantially flat circular top *g* joined to the shell *b* by a preferably sloping wall *h* which, when the thread holes or openings are formed therein, constitutes a metal shank of, what may be described as "turret-shape" or substantially so, as distinguished from the known "dome-shank" buttons.

By means of suitably constructed punches, the thread holes or openings *i*, (whereof there are preferably four arranged in pairs, diametrically opposite each other, as shown) are formed, not by merely piercing the shank, nor by wholly removing portions of the wall *h* of the shank—either of which methods fails to provide non-cutting edges for the holding thread—but, by partly severing the material at appropriate places around the wall *h*, leaving each so partly severed piece *j* connected to the shank at the part around which the button holding thread is sewn. These partly severed pieces *j* are then turned over (either by the punches, or in a second operation) against the inner side of the shank top, so as to form smooth curved edges by which the sewing thread is not liable to be cut. When the partly severed portions are turned in, these may be channeled or rounded at the parts engaged by the threads (as is shown in Fig. 6), which are thereby caused to arrange themselves centrally with relation to the width of the openings, in sewing the button to a garment, or other article.

By means of my said invention greater room can be provided between the shank and the edge of the button than is possible with the known domed-metal-shank button.

Moreover there is no possibility of the attaching thread being cut by contact with sharp or jagged edges, and there is a substantially flat surface contact between the shank top and the material, and the insertion of the needle through the openings is greatly facilitated, as the substantially flat shank top forms a guide for said needle.

Buttons having shanks made according to this invention may of course be covered with various materials or provided with fancy centers or rims as shown in Figs. 7 to 9 or with other ornamentations as is now done in the case of other well-known kinds of buttons.

Fig. 6 illustrates an example of a button which can revolve around its shank. In this case the shank *f*, is formed from a shell *k* which is placed between the front and back shells *a* and *b* forming the button, and pro-

jects through an opening in the back shell so as to permit the button to turn about its shank *f*.

I claim:—

A button having a hollow metal shank in 25 which thread holes are formed by turning inwardly the metal cut away from the shank wall at the widest portion of such holes, so as to form a protecting edge extending the full width of the hole at that part adapted 30 to be engaged by the button securing thread, substantially as set forth.

In testimony whereof I have signed my name to this specification in the presence of two subscribing witnesses.

HENRY LEWIS DAVIS.

Witnesses:

MARY RISCON,
HERBERT WILLIAM WAINWRIGHT.
